BEER TAP

Elmer G. Steffen, Milwaukee, Wis., assignor to
 Milwaukee Gas Specialty Company, Milwaukee,
 Wis., a corporation of Wisconsin

Application January 26, 1934, Serial No. 708,347

5 Claims. (Cl. 225—3)

This invention relates to taps for connecting the delivery tube of a draft apparatus to beer barrels or other liquid containers from which the contents are drawn off by a draft tube.

5 Taps of the character to which my invention relates have a nipple or equivalent coupling element by which the gas supplying hose may be attached to the tap for placing the barrel under pressure to force its contents out through the draft tube. These nipples extend laterally outward from the taps intermediate the ends thereof and in the taps as heretofore employed are not adjustable to free the chime or other obstruction, on the barrel which may hinder, if not prevent, the application of the tap to the barrel should the tap attaching fitting on the barrel be located close to the obstruction and have its locking lugs for the tap disposed to cause the nipple to contact with the obstruction on positioning the tap to engage the fitting. In a connection of this kind, the tap is pushed axially onto the fitting and then turned to carry the lugs on the tap under those on the fitting. The fitting lugs are inclined on their undersides to draw the tap into tight engagement with the fitting. The smaller ends of the fitting lugs are reversely arranged at the entrance ways between them, thus requiring a predetermined rotative position of the tap with respect to the fitting for the proper application of the tap to the fitting. Obviously, the setting of the fitting lugs with respect to the chime or other closely adjacent obstruction on the barrel is important for taps as heretofore employed, otherwise their application to the barrel is likely to be hindered, if not prevented, by the interfering obstruction.

The general purpose and object of my invention is to overcome these objections by having the nipple adjustably mounted on the tap, whereby the nipple may be set to free the chime or other closely adjacent obstruction on the barrel should such obstruction interfere with the application of the tap to the barrel in any other position of the nipple.

45 A further object of my invention is to provide for this adjustment by having the support for the nipple rotatable about the longitudinal axis of the tap and the nipple extending outwardly through a slot in the tap in transverse relation to its axis and of a length sufficient for the adjustment of the nipple for the purposes referred to.

50 A further object of my invention is to provide the slot with recesses in the form of widened por-

tions at its opposite ends whereby the nipple may enter the recesses and not hinder the relatively axial movement of the nipple support and the outer casing of the tap on the application of the tap to its attaching fitting on the barrel or other container with which the tap is usable.

5 A further object of my invention is to employ the slidably and rotatably mounted draft tube receiving bushing in the tap as the nipple support and use the spring means of that bushing for normally maintaining the nipple free of the recesses of the slot on the removal of the tap from its fitting.

Other and further objects of my invention will appear from the following specification taken in connection with the accompanying drawing, in which—

Fig. 1 is a top plan view of a barrel having a chime extending about its head or top wall and equipped with a tap attaching fitting of the type heretofore described and disposed in closely spaced relation to the chime as frequently occurs in liquid containers of this type;

Fig. 2 shows the tap of my invention applied to a tap fitting located as in Fig. 1 and illustrating the manner in which the nipple of the tap may be adjusted to clear the chime of the barrel, the showing being on a larger scale than that of Fig. 1, and the tap being in section at the nipple;

Fig. 3 is a vertical sectional view, with parts in elevation, taken on line 3—3 of Fig. 2;

Fig. 4 is a similar view taken on line 4—4 of Fig. 2; and

Fig. 5 is a perspective view of my improved tap removed from the barrel.

In the drawing, 1 indicates the top wall or head of a wooden or other barrel of the type in which the body wall 2 of the barrel continues beyond the top wall and provides the so-called chime 3 about the head of the barrel. 4 indicates a tap attaching fitting secured to the barrel head 1 in the bung opening 5 therein, said opening and the fitting 4 being located closely adjacent the chime 3 of the barrel as is a frequent occurrence in containers of this character.

The fitting 4 is secured to the top wall 1 by a nut 6 applied to the lower end of a tubular member 7 and clamped against the under surface of the top wall, as shown in Fig. 3. Member 7 extends through the bung opening 5 and projects above the top wall of the barrel where it is provided with means, as in the form of lugs 8, for detachably connecting the tap thereto.

The tap has a tubular outer casing 9 fittable

at its lower end over the upper end of the member 7 and is there provided with lugs 10 engageable under those of the fitting 4 to interlock the tap to the fitting.

5 Casing 9, in accordance with my invention, has a slot 11 in its side wall to accommodate a nipple 12 by which the gas pressure supply hose 13 is attached to the tap. Slot 11 is elongated in the direction of the circumference of the casing and is thus disposed in transverse relation to or at right angles to the longitudinal axis of the tap as shown in the drawing. The slot may have the length desired, the slot in the drawing subtending an angle of slightly more than 90 degrees.

10 Located in the casing 9 is a bushing 14. The latter extends longitudinally of the casing on opposite sides of the slot 11 and provides a support for the nipple 12. The nipple is connected at its inner end to the bushing and extends laterally outward therefrom through the slot in the casing, as shown. The bushing is rotatably mounted in the casing 9 so that the nipple may be adjusted about the axis of the casing to the length of the slot. The bushing is also slidably mounted in the casing 9 so that the casing and the bushing may have relative axial movement on the application of the tap to and its removal from the fitting 4. In applying the tap, the casing is forced downwardly over the upper end of the member 7 to position the locking lugs on the casing below those on the member 7, whereupon the casing is turned axially to interlock the lugs. A handle member 15 at the upper end of the casing is then turned to tighten the connection between the tap and its fitting and to compress a gasket 16 on the bushing 14 between the same and the upper end of the member 7. The handle 15 has screw threaded connection with the casing 9 and acts on the bushing 14 through a coiled spring 17 in the casing about the bushing.

15 Handle 15 also seals a gasket 18 against the outer side of a draft tube 19 which is extended into the barrel through the bushing 14 as shown in Figs. 3 and 4. The bore of the bushing is slightly larger in diameter than the draft tube 19 so that the gas under pressure supplied by the nipple may enter the barrel about the tube to force the liquid out of the barrel through the tube. The latter is apertured at or adjacent its lower end and is connected at its upper end to the usual dispensing faucet as in a draft apparatus.

20 Recesses 20, 20 are provided at the opposite ends of the slot 11 to increase its width beyond that of the diameter of the portion of the nipple extending therethrough. These recesses are preferably in the upper wall of the slot and serve two purposes. First, they prevent the nipple hindering the relative axial movement of the casing 9 and the bushing 14 on applying the tap to the fitting 4 and when sealing the joint at the gasket 16. The relative axial movement of the parts carry the nipple into the recess at which it is located and the recess thus holds the nipple from accidental movement out of its adjusted position.

25 When the tap is released from the fitting 4, the springs 17 forces the bushing 14 downwardly and frees the nipple from the recesses so that the nipple may be adjusted from one end of the slot to the other along its straight bottom wall which serves as a guide for the movement. The bushing 14 is maintained central in the casing 9 by having its upper end fitting in the portion of the handle 15 at the upper end of the casing and its lower end fitting against an inwardly

extending guide 21 in the casing 9 below the slot 11. The bushing 14 also carries the gasket 16 which serves to seal the joint between the tap and the fitting 4. The fitting 4 has an outside flange 22 providing a guard for the lugs on the member 7 and also serving to guide the tap into engagement therewith.

30 The adjustability of the nipple is an improvement of considerable importance. It enables a tap to be connected with a fitting without reference to the particular setting of the lugs of the fitting to the chime of the barrel. Thus, the tap is not restricted to any particular lug setting, but is usable with all settings, the nipple being adjusted for those settings which with a nipple 15 in a fixed position could not be used. The adjustable feature therefor enlarges the use of the tap and renders it generally applicable to all fittings of the character for which it is designed.

35 The advantage of the adjustable nipple is made clear in Fig. 2. With the lugs 8 of fitting 4 disposed as in Figs. 1 and 2, the tap could not be applied to the barrel with the nipple at the right hand end of the slot as indicated by the showing of the nipple at position *a*. The nipple in this position would extend over the chime 3 and contact with it before the tap could reach the fitting 4. Adjusting the nipple to position *b* at the left hand end of the slot frees the nipple from the chime and allows the tap to be applied to the fitting 4. In doing this, the lugs 10 on the tap pass downward between the lugs 8 on the fitting until below the same, whereupon the tap is turned about 90 degrees to interlock the lugs. This carries the nipple to position *c*. The tap can engage the fitting 4 in only one rotatable position, and with the nipple adjustable axially of the tap, the latter may be attached to its fitting even close to a chime, as in the drawing.

40 The details of construction and particular arrangement of parts herein shown and described may be variously changed and modified without departing from the spirit and scope of my invention except as pointed out in the appended claims.

45 I claim as my invention:

1. In a tap of the character described, an outer casing having means for releasably attaching the tap to a tap fitting on a barrel, a bushing in said casing, and a pressure hose attaching nipple carried by the bushing and extending laterally outward from the bushing through an elongated slot in the casing, said slot extending transversely of the axis of the bushing, the latter being rotatably mounted in the casing whereby the nipple may be adjusted lengthwise of the slot, said slot also serving to guide the nipple in its adjustment along the length of the slot.

2. In a tap of the character described, an outer casing having means for releasably attaching the tap to a tap fitting on a barrel, a bushing in said casing, and a pressure hose attaching nipple carried by the bushing and extending laterally outward from the bushing through a slot in the casing, said slot extending transversely of the axis of the bushing and having recesses at its opposite ends, said bushing being slidably and rotatably mounted in the casing, whereby the nipple may be adjusted to the ends of the slot and enter the recess in the relative axial movement of the bushing and the casing on attaching the tap to a fitting.

3. In a tap of the character described, an outer casing having means for releasably attaching the tap to a tap fitting on a barrel, a bushing in said casing, a pressure hose attaching nipple carried

5 by the bushing and extending laterally outward from the bushing through a slot in the casing, said slot extending transversely to the axis of the bushing and having recesses in one wall of the slot at the opposite ends thereof, said bushing being slidably and rotatably mounted in the casing, whereby the nipple may be adjusted to the ends of the slot and enter the recesses in the relative axial movement of the bushing and casing
10 10 on attaching the tap to a fitting, and spring means in the casing acting on the bushing for normally maintaining the nipple free of the recesses when the tap is removed from the fitting.
15 4. In a tap of the character described, an outer casing, having means for releasably attaching the tap to a tap fitting on a barrel, a bushing in said casing, a pressure hose attaching nipple carried by the bushing and extending laterally outward from the bushing through a slot in the casing, said slot extending transversely of the axis of the bushing and having recesses in its upper edge at the opposite ends of the slot, said bushing being slidably and rotatably mounted in the casing, whereby the nipple may be adjusted to the ends of the slot and enter the recesses in the relative axial movement of the bushing and the

casing on attaching the tap to a fitting, and spring means in the casing acting on the bushing for normally maintaining the nipple free of the recesses of the slot and adjacent the lower edge thereof when the tap is removed from the fitting, 5 the lower edge of the slot being substantially straight to guide the nipple in its adjustment to the ends of the slot.

5. A tap for connecting a draft tube to the head of a barrel having a chime about the head, comprising an outer casing for connecting the tap to the barrel head, a bushing in the casing embracing the draft tube when extended therethrough, and a pressure hose attaching nipple carried by the bushing and extending laterally 15 outward from the bushing through a slot in the casing, said slot extending transversely of the axis of the bushing, the latter being rotatably mounted in the casing whereby the nipple may be adjusted from one end of the slot to the other 20 to free the chime should the nipple when at one end of the slot interfere with the attaching of the tap to the barrel by contact with the chime, said slot also serving to guide the nipple in its adjustment along the slot. 25
